TWO-CYCLE INTERNAL-COMBUSTION
ENGINEFrederick M. Jones, Minneapolis, Minn., assignor
to U. S. Thermo Control Co., Minneapolis,
Minn., a corporation of Minnesota

Application December 24, 1947, Serial No. 793,589

8 Claims. (Cl. 123—72)

1

My invention relates to improvements in a two cycle internal combustion engine. In particular it relates to an engine of the class described having a novel means of pre-compressing the fuel charge prior to its introduction into the combustion chamber and utilizes in place of valves, internal passages within the engine, which are opened and sealed by the movement of the pistons.

In the earlier forms of two cycle engines, the fuel in the form of a compressible fluid was introduced into the crankcase of the engine and received primary compression by the downward movement of a piston during its power stroke. After the fuel charge was compressed in the crankcase in this manner, it was permitted to travel through suitable passages into the combustion area above the piston where it was again compressed prior to combustion. The undesirable feature of this arrangement was that in order to properly lubricate the crankcase and its cooperating parts and at the same time to utilize this part of the engine as a compression chamber, it was necessary to mix a portion of lubricant with the fuel and inject the mixture into the crankcase. In this arrangement the lubricant would not always be assured of reaching the several moving surfaces in sufficient quantity to properly lubricate them and, therefore, the engine was subject to excessive wear because of poor lubrication. A further disadvantage resided in the excessive use of lubricant since a considerable portion of this material would naturally be conveyed in small droplets with the fuel to the combustion chamber.

More recently engines of this type were designed with pre-compression chambers formed as an integral part of each cylinder and arranged beneath the piston but sealed from the crankcase, such as is shown in my Patent No. 2,417,253, granted March 11, 1947. Designs of this general nature did away with the intermingling of fuel and lubricant and involved a valveless engine. However, in order to provide for the passage of the pre-compressed fuel, numerous complicated passages had to be formed in the cylinders and pistons which naturally increased the cost of producing such an engine.

The present invention is directed to a two cycle engine wherein one cylinder is used for combustion purposes and another independent cylinder is used to pre-compress a fluid charge which may be either air or a hydrocarbon mixed with air, together with a simplified form of passage for transmitting the pre-compressed charge to the

2

combustion cylinder. Each of the cylinders is provided with a piston that is connected to a common crankshaft and arranged in their sequence of reciprocating movement so as to provide for the correctly timed inter-passage and ignition of the fluid charges. By this arrangement one pre-compression piston will have completed or be in the act of completing its compression stroke at the moment that a combustion piston is moving to a position where a fresh charge of compressed fluid may be introduced into the combustion cylinder. To transfer the pre-compressed charge from the one cylinder to the other, a passage extends between the two cylinders. A portion of this passage includes a passage formed within the interior of the pre-compression piston. The piston passage originates in the upper end of the piston and terminates in a side wall where it communicates with the remainder of the passage that extends to the combustion cylinder.

As an engine of this type must necessarily include at least two combustion cylinders, and it may contain any multiple of two cylinders, an equal number of pre-compression cylinders are provided so that each combustion cylinder is served by an independent pre-compression cylinder. To simplify the arrangement of cylinders and to minimize the number of passages, the two sets of cylinders are arranged in opposing parallel lines so that they form opposite lines of cylinders extending along the top of an engine casing and form a V type engine. This arrangement also enables a simplification of the fluid inlet passage to pre-compression cylinders so that an equal quantity of fluid is received in each cylinder, and it also enables the use of a single connecting passage between the two sets of cylinders to thereby avoid the use of a multiplicity of individual passages between each pre-compression cylinder and its cooperating combustion cylinder.

An object is to provide an engine of the type described having a plurality of combustion cylinders and a plurality of pre-compression cylinders extending from the top of an engine in a V arrangement with a single continuous passage joining the several cylinders to deliver the pre-compressed charges from the pre-compression cylinders to the combustion cylinders.

Another object is to provide a two-cycle engine composed of at least two combustion pistons and a corresponding number of pumping pistons which operate in combination with the combustion pistons, a crankshaft having two crank arms

disposed at an angle of 180° with respect to each other, together with means for interconnecting two non-cooperating pistons to each arm of the crankshaft so that a balanced condition is maintained between the two cooperating pairs of pistons.

Another object is to provide a two cycle engine having independent combustion and pre-compression cylinders which are laterally spaced from each other and connected by a passage, in which the timing of movement of the piston in the pre-compression cylinder is advanced with relation to the combustion cylinder piston so as to overcome the inertia of the fluid and have the same in a completely pre-compressed condition when the combustion cylinder is ready to receive the charge when the crankshaft is rotating in one direction, or to act as a pump and force the charge into the combustion cylinder when the crankshaft is rotating in an opposite direction.

Other and further objects will become apparent from the following description and claims, and in the appended drawings in which:

Fig. 1 is a front end elevation of a two cycle engine forming the present invention;

Fig. 2 is a section taken on the lines 2—2 of Fig. 1, looking in the direction of the arrows;

Fig. 3 is a section taken on the lines 3—3 of Fig. 2;

Fig. 4 is a section taken on the lines 4—4 of Fig. 2 and showing a piston in its uppermost position within a cylinder;

Fig. 5 is a vertical section taken on the lines 5—5 of Fig. 1, showing the combustion cylinders in side elevation;

Fig. 6 is a section taken on the lines 6—6 of Fig. 1 and shows in plan view a portion of the fuel inlet passage;

Fig. 7 is a sectional view taken on the lines 7—7 of Fig. 3 showing in plan view a pair of pre-compression cylinders and a pair of combustion cylinders and an inter-connecting passage therebetween;

Figs. 8 and 9 diagrammatically show the positions of opposite pairs of pistons when they are in their various extreme positions;

Figs. 10, 11, 12 and 13 show a pair of cooperating combustion and pre-compression cylinders in four different positions of their cyclic movement.

Referring now to Fig. 1, a two cycle engine indicated by the general reference numeral 14, is formed with an engine casing 15 which at its opposite ends as shown in Fig. 2, is provided with removable plates 16 and 17, which respectively carry bearings 18 and 19 to support the opposite ends of a two cycle crankshaft to be described later. The engine casing 15 is provided with a plurality of ventilating fins 20 for radiating heat from the casing 15.

Extending from the upper end of casing 15 is a combustion cylinder block 22 composed of a plurality of cylinders each having a detachable cover 24. A plurality of fins 26 are provided on the cylinder block 22 for cooling purposes. Extending from one side of cylinder block 22 is an exhaust conduit 28.

Also extending from the upper surface of engine casing 15 is a pre-compression cylinder block 30 which extends angularly from the casing so as to form an inclusive angle of substantially 45° or less with relation to cylinder block 22, as will be clearly evident in Fig. 1. Cylinder block 30 is composed of a plurality of cylinders each of which is provided with a detachable

cover 32. Block 30 is also provided with a plurality of cooling fins 34. Extending into the upper end of cylinder block 30 is a fluid inlet conduit 36 which is adapted to be connected to a source of suitable fluid.

Referring now to Fig. 7, cylinder block 22 is composed of a plurality of cylinders 38 and 40, and while here shown as being only two cylinders, it will be understood that cylinder block 22 may be composed of a larger number of cylinders such as might constitute any multiple of two. Likewise, cylinder block 30 is composed of a pair of cylinders 42 and 44 and might be composed of any larger number, provided there are an equal number of such cylinders as there are cylinders in the block 22. The two groups of cylinders form opposing lines of cylinders which extend angularly from the top of the engine casing.

Referring now to Figs. 2 and 3, a crankshaft indicated by general reference numeral 45 is mounted within engine casing 15 and is supported for rotation on the bearings 18 and 19. Crankshaft 45 is of conventional two cycle design and provided with the arm portions 46 and 48 which are spaced from each other 180° in their cycle of rotation. On either end, the crankshaft 45 is provided with extensions 47 and 49 for connection to appropriate driven members.

Joined to each of piston arm portions 46 and 48 of crankshaft 45 by a connecting rod 50 are a plurality of identical combustion pistons 52 and 52a, see Figs. 3, 5, 8 and 9, which are provided with the usual wrist pins 54 and piston rings 56. Pistons 52 and 52a are of conventional design, but for further understanding, each is provided with a raised surface 58 on its upper end which at one side is formed in a sharp curve 60 and at its other side is slanted at 62. Also connected to crankshaft portions 46 and 48 by connecting rods 64 are a plurality of identical pre-compression pistons 66 and 66a, see Figs. 2, 3, 8 and 9, having the usual wrist pin connections 68, and adjacent their upper and lower extremities, the usual piston rings 70.

Referring now to Fig. 4, piston 66 is shown in cross section, it being understood that pistons 66 and 66a are identical in construction. Shown as slopingly extending from the side of one wall of the piston to a lower extremity on the other wall is a web 72 which forms a chamber 74 on the lower end of the piston which is open at its lower extremity, and which houses the wrist pin 68 that connects the piston to piston rod 64. Above web 72 and open through the upper surface of the piston 66 is a second chamber 76, which is sealed from chamber 74 by web 72. Extending downwardly from chamber 76 is a vertical passage 78 which terminates in an opening 80 extending through the lower side wall of the piston. As shown in Figs. 2 and 4, a short web 82 extends at right angles from web 72 to the adjacent piston wall and divides opening 80 so as to provide support for web 72 and also to strengthen the piston wall on either side of opening 80.

Referring now to Fig. 7 in conjunction with Fig. 2, it will be understood that a first combustion piston 52 will be mounted in cylinder 38, and an identical piston 52a will be mounted in cylinder 40. A first pre-compression piston 66a will be mounted in cylinder 42, and an identical piston 66 will be mounted in cylinder 44. The pistons 52 and 52a of cylinders 38 and 42, as shown in Figs. 8 and 9, are connected to portion 48 of crankshaft 45 and will reciprocate in unison with

each other. Similarly the pistons 52a and 66 in cylinders 40 and 44 are connected to portion 46 of crankshaft 45 and will also reciprocate in unison. Thus it follows that the pistons 52 and 66 in cylinders 38 and 44, and also the pistons 52a and 66a in cylinders 40 and 42 reciprocate in opposite directions with relation to each other and form a cooperating pair of pistons. Therefore, as will be set forth in detail hereinafter, each pre-compression cylinder cooperates with an obliquely disposed combustion cylinder and in this relationship, and particularly as shown in Figs. 3 and 10-13, they form a cooperating pair of cylinders.

As will be evident from an examination of Figs. 8-13, the two pistons forming a pair of cooperating pistons extend angularly with relation to each other, but they are both connected to the same crankshaft. The angle which they extend from the crankshaft has an important effect on the timing of the reciprocation of the pistons. As shown in Figs. 8 or 13, when piston 52 is at its lowest position, the head of its cooperating pre-compression piston 66 is spaced slightly from the top of cylinder 44. Likewise, as shown in Fig. 12, when piston 66 is at the top of its compression stroke, piston 52 has not quite finished its power stroke. Actually, piston 66 is moving slightly ahead of piston 52 so that the fluid is completely compressed and its inertia overcome prior to the time that piston 52 and its cylinder is ready to receive a fresh fluid charge. This is an important feature when the engine is of a high speed type.

Referring now to Fig. 6 in conjunction with Figs. 1, 3 and 4, the fluid inlet 36 connects to a passage 84 in cylinder block 30 and passes arcuately about cylinder 42 to a triangularly shaped opening 86 which extends downwardly within the cylinder block to a passage 88, shown in Fig. 7. The downwardly extending passage 86 joins the center of passage 88 between cylinders 42 and 44 and extends arcuately about each of cylinders 42 and 44 as shown at 90 and 92. A plurality of inlet passages 94 extend through the wall of cylinder 42 and another plurality of passages 96 extend through the wall of cylinder 44. The passages 94 and 96 are to provide inlet for the fluid to each of cylinders 42 and 44. On their diametrically opposite sides cylinders 42 and 44 are provided with outlet passages 98 and 100 which join to a large common passage 102, which extends from the outlet sides of cylinders 42 and 44 in cylinder block 30 to a plurality of passages 104 and 106 in the side walls of cylinders 38 and 40 of cylinder block 22. Cylinders 38 and 40 on their other sides are provided with exhaust passages 108 and 110, which join a common exhaust passage 112 that extends to the exhaust passage 28, shown in Fig. 1.

An engine of the type described may be used as a gasoline engine, in which case the fluid charge will be a mixture of gasoline and air, and the same is ignited by conventional spark plugs such as is shown in dotted lines in Fig. 3, and indicated by reference numeral 114. However, the engine may also be used as a compression ignited engine usually referred to as a Diesel type engine. When used in the latter manner, the pre-compressed fluid is air, and the spark plugs 114 are replaced by suitable means of injecting fuel directly into the combustion cylinders. As shown in the several figures of the drawings, the pre-compression and combustion cylinders and

6
pistons are of substantially equal size, but it should be understood that when used in a Diesel combination the pre-compression cylinders and pistons may be of larger size than the combustion cylinders and pistons and that other variations may be made in the size of the passages.

While not specifically described, the engine would be lubricated in a conventional manner by a forced feed lubricating system not illustrated.

- 10 The operation of the engine will now be explained in detail. By referring to Figs. 2, 7, 8 and 9, it will be apparent that a combustion piston 52 and a pre-compression piston 66a would be joined to portion 48 of the crankshaft 15 45 and another pair of combustion and pre-compression pistons 52a and 66 would be joined to crankshaft portion 46. In each case the relatively opposite pistons connected to a single portion of the crankshaft would operate together 20 and in unison, as shown in Figs. 8 and 9, so that with this arrangement a combustion piston 52 in cylinder 38 will have reached the lower extremity of its reciprocating movement when a pre-compression piston 66 in cylinder 44 will be in a relatively opposite position. Likewise, a combustion piston 52a in cylinder 40 will cooperate in the same manner with a pre-compression piston 66a in cylinder 42. It further being understood that the respective pistons 52 and 52a in cylinders 30 38 and 40 reciprocate in opposite directions as is equally true of the pre-compression pistons 66 and 66a in cylinders 42 and 44.

Fluid, such as air or an air-gas mixture, is introduced into cylinder block 30 through the inlet 36, passage 84, downwardly extending passage 86, and thence equally distributed in both directions through portions 90 and 92 of the lower passage 88.

Referring now to Fig. 2, in conjunction with 40 Figs. 7 and 10, the pre-compression piston 66 in cylinder 44 is at its lowermost position so that fluid in passage 88 is free to enter the several inlet openings 96 above the upper end of the piston. At the same time the combustion piston 52 in 45 cylinder 38 is approaching its uppermost extremity and the openings 100 and 106 on either end of passage 102 are closed.

Referring now to Fig. 11, an explosion has just 50 occurred in cylinder 38 and has forced piston 52 to move downwardly and piston 66 to move upwardly to the extent that the inlet openings 96 in cylinder 44 are now closed by the pre-compression piston 66, but the piston has not yet reached a position where openings 100 in the cylinder wall 55 are in communication with the opening 80 at the lower end of passage 78 in the piston. Under these conditions the fresh charge of fluid is being compressed in cylinder 44.

Referring now to Fig. 12, piston 66 has reached 60 its extreme upper position in cylinder 44 and the opening 80 at the lower extremity of the piston is now in alignment with the openings 100 and the cross passage 102, and the compressed fluid within chamber 76 is now free to flow through passage 65 78 and enter passage 102. However, piston 52 is still sealing the openings 106 and, therefore, the fresh fluid charge cannot yet enter cylinder 38. However, the passage 102 has sufficient capacity to hold the compressed charge. At the 70 same time that the charge is being delivered to passage 102 it will be noted that the openings 110 are now partially in communication with the area above piston 52 and the exhaust gases can commence to pass from the interior of cylinder 75 38 through the openings 110.

Referring now to Fig. 13, piston 52 has reached its lowermost extremity and piston 66 has started to move downwardly. Under these conditions the compressed charge of fluid is free to leave passage 102 and enter the openings 106 in cylinder 38 where it contacts the curved surface 60 on the head 58 of piston 52 and is turned upwardly within cylinder 38 to aid in purging the spent gases past the slanting surface 62 of the piston head through opening 110.

As has been previously pointed out, the two cylinder blocks are angularly disposed with relation to each other so as to form an inclusive angle of 45° or less. This arrangement causes one of the pistons forming a cooperating pair of pistons to move slightly in advance of the other piston even though the pistons are connected to opposite arms of the crankshaft. In Figs. 10-13 the crankshaft is shown as rotating in a counter-clockwise direction and the pre-compression piston 66 is moving in advance of the combustion piston 52. This action permits the piston 66 to complete its compression stroke prior to the time that piston 52 uncovers the opening 106. Thus the inertia of the charge is offset and it is in a fully compressed condition in passage 102 when piston 52 uncovers opening 106. Such an arrangement is highly desirable if the engine is to be used for high speed operation.

If, however, the crankshaft is rotated in a clockwise direction, piston 52 moves in advance of piston 66 and in that case piston 52 will be in the position of Fig. 13 when piston 66 is in the position of Fig. 12. This permits the compressed charge to be delivered from passage 78 through passage 102 to cylinder 38 directly and at the instant that piston 52 uncovers opening 106. Rotation of the crankshaft in a clockwise direction is desirable if the engine is to be used for slow speed operation since under these conditions piston 66 is giving a direct pumping action which will give better scavenging of the burn gases in cylinder 38.

In the foregoing an explanation has been given of the operation of the combustion piston 52 in cylinder 38 and a pre-compression piston 66 in cylinder 44. It will be understood that a combustion piston 52a in cylinder 40 and a pre-compression piston 66a in cylinder 42 will be reciprocating in exactly opposite directions so that the power necessary to continue the movement of the pistons 52 and 66 in cylinders 38 and 44 as shown in Fig. 13 will be supplied by a combustion and power stroke of the similar piston 52a in cylinder 40.

Referring to Fig. 7, it will now be evident that the single passage 102 which connects the pair of pre-compression cylinders with the pair of combustion cylinders is operative to provide a common communication between the pairs of cylinders, but since the cooperating pairs of cylinders operate in cycles of 180° with relation to each other, the common passage 102 is operable to supply fluid from one pre-compression cylinder to one combustion cylinder and the other cylinders will be sealed until their respective pistons have reached the predetermined position, such as is shown in Figs. 12 and 13, where they in turn are operative to deliver fluid one to the other.

The advantages of my invention result from the simplicity of structure which reduces the number of passages within the cylinder blocks and the engine casing by utilizing the longitudinal passages through the pre-compression pistons 66 and 66a to deliver the fluid when it has

reached its maximum degree of compression. Furthermore, this single common passage 102 between the two cylinder blocks simplifies the construction for delivering the fluid from the pre-compression portion of the engine to the combustion portion of the engine.

My invention is not restricted to the single illustration, but is defined in the terms of the appended claims.

10 I claim:

1. A two cycle engine, comprising an engine casing, a first pair of cylinders extending from said casing forming two combustion chambers, a second pair of cylinders extending from said 15 casing forming two pre-compression chambers, each of said pairs of cylinders extending angularly from said casing in opposite relation to the other pair of cylinders in a manner as to form an inclusive angle which is not in excess of 45° between the respective pairs of cylinders, a crankshaft positioned in the casing, a piston in each cylinder and connected to the crankshaft in such a manner that the pistons in each pair of cylinders simultaneously reciprocate in opposite directions, means for conducting fluid to the pair of pre-compression chambers, and a passage extending between the first and second pairs of cylinders, said passage forming a common communication between all of the cylinders for the 20 passage of pre-compressed charges from the second pair of cylinders to the first pair of cylinders in such a manner that each combustion cylinder receives through the common passage a pre-compressed charge from its obliquely opposite pre-compression cylinder.

2. A two cycle engine, comprising an engine casing, a first line of cylinders extending from said casing and forming a line of combustion chambers, a second line of cylinders extending from said casing in parallel relationship to the first line of cylinders and forming a line of pre-compression chambers, each of said lines of cylinders extending angularly from the casing in a manner as to form an inclusive angle of substantially 45° between the lines of the cylinders, a piston in each cylinder, a crankshaft positioned in said casing and connected to each of said pistons in such a manner that the piston in one combustion chamber reciprocates in an opposite direction to the piston in the next adjacent combustion chamber and in unison with the piston situated in the substantially opposite pre-compression chamber, and a passage extending between the first and second lines of cylinders forming a common communication between all of the chambers forming both of said lines of cylinders whereby a first cylinder from either end in the line of pre-compression chambers is operable to supply fluid fuel through said passage to an obliquely opposite second cylinder in the line of combustion chambers.

3. A two cycle engine, comprising an engine casing, a first line of cylinders extending from said casing and forming a group of combustion cylinders, a second line of cylinders extending from said casing in spaced relation to the first line of cylinders and forming a group of pre-compression cylinders, and a passage extending 65 between the second and first lines of cylinders forming a common communication between all of the cylinders forming both of said lines of cylinders for the passage of pre-compressed charges from the second line of cylinders to the first line 70 of cylinders.

4. A two cycle engine, comprising an engine casing, a first line of cylinders extending from said casing and forming a group of combustion cylinders, a second line of cylinders extending in spaced relation to said first line of cylinders and forming a group of pre-compression cylinders, means associated with said second line of cylinders for cooling the same and forming a first means of cooling the pre-compressed charges, and a passage extending between the second and first lines of cylinders forming a common communication between all of the cylinders forming both of said lines of cylinders, said passage forming a second means of cooling the pre-compressed charges before the same enter the first named cylinders.

5. A two cycle engine, comprising a crankshaft having a pair of spaced apart crank-arms disposed at an angle of 180° with respect to each other, a working piston connected to one of said arms, a pumping piston connected to the other of said arms to normally reciprocate in a direction opposite to the working piston, a passage for conducting pressurized fluid from the pumping piston to a point above the head of the working piston, and a pair of cylinders surrounding said pistons and connected to the opposite ends of said passage, said cylinders being disposed at an angle of substantially 45° with respect to each other to cause both of said pistons to momentarily move in the same direction for a short distance so that when the crankshaft rotates in one direction the charge is delivered in a fully compressed condition to the communicating passage by the pumping piston prior to the time that the working piston is in a position to permit entry of the charge into the combustion chamber and when the crankshaft is rotated in an opposite direction the charge is delivered to the communicating passage by the pumping piston at the same instant that the working piston is in a position to permit entry of the charge into the combustion cylinder.

6. A two-cycle engine, comprising two combustion pistons, two pumping pistons, a crank-shaft having two laterally spaced crank arms disposed along the axis of the crankshaft at an angle of 180° with respect to each other, and two pairs of connecting rods, the rods forming each pair of connecting rods being laterally disposed in side-by-side relationship with each other along the axis of the crankshaft, the outer ends of each pair of rods respectively connected to a combustion piston and a pumping piston, the inner ends of each pair of rods independently connected to the same crank arm.

7. A two-cycle engine, comprising an engine casing, a first pair of cylinders extending from said casing forming combustion chambers, a second pair of cylinders extending from said casing forming precompression chambers, a piston in

each of said cylinders, a crankshaft carried within said casing having two laterally spaced crank arms disposed at an angle of 180° with respect to each other along the axis of the crankshaft, two pairs of connecting rods, the rods forming each pair of connecting rods being laterally disposed in side-by-side relationship with each other along the axis of the crankshaft, the outer ends of each pair of rods respectively connected to a combustion piston and a precompression piston, the inner ends of each pair of rods independently connected in side-by-side relationship to the same crank arm, and a passage joining all of the cylinders and forming a common communication between the cylinders for the passage of precompressed charges from the second pair of cylinders to the first pair of cylinders.

8. A two-cycle engine, comprising an engine casing, a first pair of cylinders extending from said casing forming combustion chambers, a second pair of cylinders extending from said casing forming precompression chambers, each of said pairs of cylinders extending angularly from the casing in opposite relation to the other pair of cylinders to form an inclusive angle between said pairs of cylinders, a piston in each of said cylinders, a crankshaft carried within the casing having two laterally spaced crank arms disposed at an angle of 180° with respect to each other along the axis of the crankshaft, two pairs of connecting rods carried within the casing for joining the pistons to the crankshaft, the rods forming each pair of connecting rods being laterally spaced in side-by-side relationship with each other along the axis of the crankshaft, the outer ends of each pair of rods respectively connected to a combustion piston and a precompression piston, the inner ends of each pair of rods independently connected in side-by-side relationship to the same crank arm, whereby the inclusive angle between the pairs of cylinders can be varied and fixed at any angle, and a single passage extending between the first and second pairs of cylinders, said passage forming a common communication between all of the cylinders for the passage of precompressed charges from the second pair of cylinders to the first pair of cylinders.
